NICHOLAS S. VEDDER AND FRANCIS RITCHIE, OF TROY, ASSIGNEES TO
RUSSELL WHEELER, OF UTICA, NEW YORK,

Design No. 4,611, dated January 24, 1871.

DESIGN FOR A COOKING-STOVE.

The Schedule referred to in these Letters Patent and making part of the same.

To all whom it may concern:

Be it known that we NICHOLAS S. VEDDER and FRANCIS RITCHIE, of the city of Troy, in the county of Rensselaer and State of New York, have invented and produced a new and original Design for a Cook-Stove, of which the following is a specification.

The photographic illustration accompanying this specification and forming a part thereof shows a side and front elevation of a cook-stove with my design cast upon the oven-door, and also upon the panel of said stove.

The first part of my design consists in a compound ornament, composed of scroll-work and bead-work, surmounted with an arch, from whose top issue flames.

The exact shape of this compound ornament, and the details of its configuration cannot be described, but are apparent upon an inspection of the above-mentioned photograph.

The ornament is there fully shown, and is seen upon the center of the oven door, and also upon the raised panel.

This compound ornament is cast on and forms part of a plate of a stove and is applicable to the side, to a panel, a door, and the like, of any stove.

The second part of my design consists in the combination with this compound ornament of an ornamental border-molding or moldings.

Around the outer border of the oven door is a molding representing a twisted cord. Within this cord-molding is a bead-molding extending around the inner border of said door.

Around the panel which contains the compound ornament runs a bead-molding.

There is no molding of twisted cord around said

panel, but, if deemed advisable, it will be added to the panel as it now is to the oven-door. These moldings are cast on in the same manner as the compound ornaments are.

I do not limit the application of my compound ornament, or its combination with the moldings mentioned, to any particular kind of stove or to any particular part thereof.

I propose to use the said compound ornament either with or without one or both of said border-moldings.

Claim.

We claim—

1. The compound ornament cast on and forming part of any stove, substantially as herein shown and described.

2. The combination of the compound ornament and the ornamental border-moldings of bead and rope-work arranged together and cast upon any stove, substantially as shown and described.

3. The combination of the compound ornament and the bead-molding for border, arranged together and cast upon any stove, substantially as shown and described.

4. The combination of the compound ornament and the twisted cord-molding for border, arranged together and cast upon any stove, substantially as herein shown and described.

NICHOLAS S. VEDDER.
FRANCIS RITCHIE.
